LIGHTWEIGHT HEADSET

Daniel H. Christian, Corinth, Miss., and George L. Payne,
Bedford Hills, N.Y., assignors to International Telephone
and Telegraph Corporation, New York, N.Y.

Filed Feb. 1, 1973, Ser. No. 328,880

Term of patent 14 years

Int. Cl. D14—03
U.S. Cl. D26—14 H

FIG. 1

FIG. 2

FIG. 3

FIG. 4**FIG. 5****FIG. 6**

FIG. 1 is a perspective view as seen from the front of our design for a lightweight headset, in a first operational position;

FIG. 2 is a perspective view as seen from the right side with headset in the position of FIG. 1;

FIG. 3 is a left side view of the headset in the position of FIG. 1;

FIG. 4 is a top plan view of the headset in the position of FIG. 1;

FIG. 5 is a rear view of the headset in the position of FIG. 1; and

FIG. 6 is a perspective view of the headset employing our design in a second operational position.

We claim:

The ornamental design of a lightweight headset, substantially as shown as described.
